UNITED STATES PATENT OFFICE

1,932,394

FLOATING ROOF

Harry C. Boardman, Chicago, Ill., assignor to
 Chicago Bridge & Iron Company, Chicago, Ill.,
 a corporation of Illinois

Application August 13, 1932. Serial No. 628,752

10 Claims. (Cl. 220—26)

This invention relates to improvements in floating roofs and more especially such roofs adapted for use in connection with liquid containers, for example, containers adapted to hold volatile oils 5 and the like.

In tanks of the character referred to it is customary to provide a roof that floats on the surface of the liquid and rises and falls therewith as liquid is taken from or put into the tank. 10 Among the features of my invention is the provision of roofs of this character that have increased buoyancy and stability over those heretofore used.

Another feature of my invention is the provision of means for collecting vapors and gases 15 under the roof and preventing the uneven distribution of the same, thus increasing the stability of the roof and lessening or preventing tendencies of the same to chip.

20 Other features and advantages of my invention will appear in full as I proceed with my specification.

In those forms of devices embodying the features of my invention shown in the accompanying drawings:

Fig. 1 is a top plan view;

Fig. 2 is a vertical sectional view of the roof of Fig. 1;

Fig. 3 is a view similar to Fig. 2 showing a 30 modification taken as indicated by the line 3 of Fig. 4;

Fig. 4 is a bottom plan view of the roof of Fig. 3 taken as indicated by the line 4 of Fig. 3;

Fig. 5 is a view similar to Fig. 3 showing a 35 modification taken as indicated by the line 5 of Fig. 6;

Fig. 6 is a bottom plan view of the roof of Fig. 5 taken as indicated by the line 6 of Fig. 5;

Fig. 7 is a view similar to Fig. 5 of a modification taken as indicated by the line 7 of Fig. 8; and

Fig. 8 is a bottom plan view of the roof of Fig. 7 taken as indicated by the line 8 of Fig. 7.

As shown in the drawings, the invention is illustrated in each case for use in connection with a cylindrical tank.

In the form shown in Figs. 1 and 2 the side wall or shell of the tank is indicated by 10 and 50 the bottom by 11. The roof as here shown includes a central flat sheet-metal portion 12 supported by an annular open-bottom pontoon 13 projecting above the plane of the central sheet-metal portion 12. The outer edge of the pontoon 13 is provided with a depending rim 14 extending

below the plane of the central sheet-metal portion 12.

Any suitable sealing means may be employed for sealing or closing the space 15 between the periphery of the roof and the shell 10 of the 60 tank. Many varieties of such sealing means are now well known in the art and consequently none need be described in detail here. It will suffice to say that such sealing means may include a plurality of shoes or plates 16 supported from the 65 edge of the roof by suitable means, for example, the angular bar 17 held at the upper ends of the pivoted levers 18—18. Springs 19 may be employed for yieldingly urging the shoes 16 outwardly into contact with the shell of the tank. 70 20 may indicate a flexible seal, for example, fabric, for sealing the space between the shoes and the upper outer edge of the pontoon 13; and similar fabric (not shown) may be employed for sealing the spaces between the vertical edges of the 75 shoes 16.

Since the pontoon 13 projects above the plane of the central portion 12, it forms an upstanding rim 21 at the outer edge of the central circular sheet 12, which rim may be employed to retain 80 water, for example rain water, on top of the central portion 12. This water may serve to insulate the roof and assist in keeping the fabric or liquid under the same cool. Since the pontoon extends above the plane of the sheet portion 12, it will 85 be seen that such pontoon will impart buoyancy to the roof even after the sheet metal portion 12 is submerged. If desired, the roof may have enough buoyancy so that even if the central portion is entirely filled with rain water up to the 90 level of the top of the pontoon 13, the roof will still float provided the space in the pontoon above the plane of the central portion 12 (extended) remains substantially filled with gas.

It will be seen that by extending the outer rim 95 14 of the pontoon below the level of the plane (extended) of the central portion 12, there is provided a gas-receiving space under the entire roof. That is, gases can collect and will be retained not only in the pontoon but also under 100 the central sheet-metal portion 12. There may, however, be such a small amount of gas that it will all be in the upper part of the annular pontoon, in which case the central sheet-metal portion 12 will rest in contact with the liquid.

The form of device shown in Figs. 3 and 4 is substantially the same as described except that I have provided on the under side of the roof radial partitions or bulkheads 122. As here shown, there are eight of these partitions radiat- 110

ing from the center 123. The lower edges of these partitions are even with the lower edge of the depending rim 114 at the periphery of the roof. In this form the central sheet-metal portion of the roof is indicated by 112, the open-bottom pontoon by 113, and the upstanding rim formed by the pontoon at the periphery of the central part 112 is indicated by 121. It is to be understood that this roof is to be used in connection with a tank as shown in Figs. 1 and 2 with a suitable seal; and in other patents, not shown here, the roof of Figs. 3 and 4 is constructed and operates substantially the same as the roof of Figs. 1 and 2. In the form of device shown in Figs. 3 and 4, however, the partitions 122 serve to assist somewhat in preventing an uneven distribution of gas under the roof. For example, if there is some gas under the roof and the roof tips or tends to tip somewhat, the gas is prevented by the partitions 122 from all flowing around to one side. These partitions, therefore, in lessening the uneven distribution of gas, increase the stability of the roof.

The form shown in Figs. 5 and 6 has the outer depending rim 14 or 114 omitted. The shoes or other seal used are employed in the place of this outer rim. In the form of Figs. 5 and 6, also, the rim corresponding to the rim 121 at the inner periphery of the annular pontoon is extended somewhat below the plane of the central sheet-metal portion.

Describing the form of Figs. 5 and 6 more particularly, the central sheet-metal portion is indicated by 212, the annular open-bottom pontoon by 213, said pontoon projecting above the central sheet 212 to form the upstanding rim 221. There is no rim like 14 or 114 at the outer edge of the pontoon. Instead of this, the sealing shoes 216 together with the fabric seal 220 are employed to assist in retaining gases under the roof, the lower edges of the shoes extending considerably below the plane (extended) of the central sheet 212. The lower edges of the shoes are indicated by 216a. It is to be understood that the shoes 216 are supported in a manner similar to the way in which the shoes 16 of Figs. 1 and 2 are supported, and that the seal is substantially the same as is described in connection with the device of Figs. 1 and 2; or any other seal well known in the art may be employed.

In the form of Figs. 5 and 6 there is provided a downward extension of the rim 221, said extension or depending rim being indicated by 221a. In the form of Figs. 5 and 6 there are also provided radial partitions or bulkheads 222 extending from the center 223 outwardly to the depending rim 221a.

In the form of Figs. 5 and 6 the shell of the tank is indicated by 210.

The form shown in Figs. 7 and 8 is provided with depending rims at both the outer and inner edges of the pontoon and is also provided with bulkheads extending radially from the center to the outer edge of the pontoon. In the form of Figs. 7 and 8 the central sheet portion is indicated by 312 and the open-bottom pontoon by 313. The depending rim at the outer edge of the pontoon is indicated by 314 and at the inner edge of the pontoon there is provided a depending rim 321a similar to the rim 221a of the device of Figs. 5 and 6. The pontoon 313 forms an upstanding rim at the periphery of the sheet 312 as indicated by 321.

The roof of Figs. 7 and 8 is provided with radial 75 depending partitions or bulkheads extending from

the center 323 of the roof outwardly to the rim 321a. These bulkheads are indicated by 322 and there are provided extensions of the same, 322a, extending from the inner pontoon rim 321a to the outer pontoon rim 314.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I regard as new and desire to secure by Letters Patent is:

1. A floating roof comprising, a substantially flat central portion of substantial proportion, said portion having an upstanding peripheral wall constituting a portion of an open-bottom annular pontoon, said upstanding wall having connected thereto a downwardly extending annular-like member constituting another portion of said pontoon.

2. A floating roof as claimed in claim 1, in which the downwardly extending annular-like member extends below the plane of the flat central portion.

3. A floating roof as claimed in claim 1, in which the inner edge of the pontoon is provided with a depending rim extending below the plane of the flat central portion.

4. A floating roof as claimed in claim 1, in which the downwardly extending annular-like member extends below the plane of the flat central portion and in which the inner edge of the pontoon is provided with a depending rim extending below the plane of the flat central portion.

5. A floating roof as claimed in claim 1, with depending partitions on its underside forming separate open-bottom gas-receiving spaces under the roof, said partitions serving to lessen an uneven distribution of gases under the roof.

6. A floating roof as claimed in claim 1, with depending radial partitions on its underside forming separate open-bottom gas-receiving spaces under the roof, said partitions serving to lessen an uneven distribution of gases under the roof.

7. A floating roof as claimed in claim 1, with depending partitions on the underside of the flat central portion forming separate open-bottom gas-receiving spaces under said flat central portion, said partitions serving to lessen an uneven distribution of gases under said flat central portion.

8. A floating roof as claimed in claim 1, with depending radial partitions on the underside of the flat central portion forming separate open-bottom gas-receiving spaces under said flat central portion, said partitions serving to lessen an uneven distribution of gases under said flat central portion.

9. A floating roof as claimed in claim 1, with depending partitions in the pontoon forming separate open-bottom gas-receiving spaces in said pontoon, said partitions serving to lessen an uneven distribution of gases in said pontoon.

10. A floating roof as claimed in claim 1, with depending radial partitions in the pontoon forming separate open-bottom gas-receiving spaces in said pontoon, said partitions serving to lessen an uneven distribution of gases in aid pontoon.
